UNITED STATES PATENT OFFICE

2,167,424

PIPE OR TUBE MAKING.

Edward J. Novack, McKeesport, Pa., assignor to
 National Tube Company, a corporation of New
 Jersey

Application March 29, 1938, Serial No. 198,784

3 Claims. (Cl. 80—13)

This invention relates to the manufacture of pipes or tubes and, more particularly, to apparatus for internally lubricating billets and tubular work-pieces while being made into seamless pipes or tubes.

In the forming of tubular work-pieces by the axial rolling process the need for lubricating the interior surface of the wall of said work-piece during its formation, at the surfaces of contact between the mandrel-plug and the work-piece, is well known. I have found that the best method of such lubrication is by depositing a film of carbon by the partial combustion of a solid or liquid material containing carbon, such as oil or coal dust. This can be effected in the working zone of the mill, as there is not sufficient oxygen to permit complete combustion of the oil or other lubricant used although the temperature is very high.

It is accordingly an object of the present invention to provide an improved apparatus for lubricating the mandrel-plug of a pipe or tube mill.

It is another object of the present invention to provide an improved apparatus for lubricating the piercing-point of a pipe or tube mill.

It is a further object of my invention to provide an improved apparatus of the class described which is continuous and automatic.

The foregoing and further objects will be apparent after referring to the drawings, in which:

Figures 1 and 1^a are composite longitudinal sectional elevations of the apparatus of the invention;

Figure 2 is an enlarged fragmentary sectional view of part of the apparatus of Figure 1;

Figure 3 is a fragmentary sectional view of the apparatus of my invention operating on a previously pierced or hollow billet; and

Figure 4 is a fragmentary sectional view of the apparatus of my invention as used for reeling a previously pierced and elongated tubular work-piece.

In the drawings the letter A designates a pair of power-actuated metal-working rolls adapted to pierce and elongate a billet B by drawing it over the mandrel-plug or piercing-point C of the apparatus of my invention. The numeral 2 designates a mandrel-bar having a bar-cap 3 at its outer end. Disposed on the bar-cap 3 is the piercing-point C. This piercing-point C has a bore 5 therein extending from the rear thereof to a point adjacent the tip 6, and may have a chamber 7 therein. A recess 8 around the periphery of said piercing-point is provided ad-

jacent the tip 6 and communicates with the bore 5 by means of ports 9 so that a lubricant supplied to the piercing-point C will be delivered through the bore 5 and ports 9 to the inner surface of the billet B and the exterior of the piercing-point.

The piercing-point C is reciprocably disposed on the forwardly extending portion 11 of the bar-cap 3 and has a rearwardly extending central portion 12 adapted to extend into the bore 14 of the bar-cap 3, the bore providing, at this point, a valve chamber 15. Within the valve chamber 15 there is disposed a valve 16 and its spring 17 which normally holds the valve in closed position against the valve-seat 18. When in this position the piercing-point C is pushed forwardly by reason of the engagement of the valve 16 with its rearwardly extending central portion 12.

Concentrically disposed within the mandrel-bar 2 are telescoped pipes 19 and 20. The inner pipe 19 is in communication with the bore 14 in the bar-cap 3 and the outer pipe 20 is open at its forward end, as shown at 21. The rear end 22 of the mandrel-bar 2 is connected by a coupler 25 to a thrust-spindle 26 disposed within a thrust-bearing 27, the latter being secured within a housing 28 in the mandrel-bar carriage 30. The mandrel-bar carriage 30 is held in its working position by the usual latch 31 and is movable toward and away from the metal-working rolls A in the conventional manner by means of a cable 32.

The concentrically disposed telescoped pipes 19 and 20 extend through the coupler 25 and the thrust-spindle 26. The inner pipe 19 is connected to a supply 35 of lubricant 36 which is under pressure. The outer pipe 20 is connected to a suitable source of cooling fluid to deliver said fluid to the interior of the mandrel-bar 2. This fluid is exhausted from the interior of the mandrel-bar 2 around pipe 20 through the outlet 38.

According to the foregoing, it will be seen that, in operation, the lubricant 36 is delivered under pressure through the pipe 19 and thence through the bore 14 to the valve chamber 15. When the billet B is forced into contact with the piercing-point C it opens the valve 16 by reason of the engagement of the rearwardly extending central portion 12 of the piercing-point with the valve 16, thereby permitting the lubricant to flow into the recess 8 and, by reason of the high temperature of the billet and the lack of oxygen, incomplete combustion takes place, there-

by depositing a film of carbon on the inner surface of the billet B. When the billet B has entirely passed over the piercing-point C the supply of lubricant to the point will be automatically shut off by the valve-spring 17 forcing the piercing-point C forwardly and closing the valve 16.

In Figures 3 and 4, I have shown the application of the apparatus of my invention to the 10 "second-piercing" and "reeling" operations, respectively. As shown in Figure 3, a previously pierced or hollow billet B is subjected to further substantial wall reduction while in Figure 4, a previously pierced and elongated work-piece B 15 is being "reeled" i. e. subjected to a wall smoothing operation without any substantial wall reduction. The mandrel-plug C and the balance of the apparatus is substantially the same as previously described.

20 While I have shown and described a specific embodiment of my invention, it will be understood that I do not wish to be limited exactly thereto, since various modifications may be made without departing from the scope of my invention, as defined by the following claims.

I claim:

1. In a pipe or tube mill, a mandrel-bar, a mandrel-plug reciprocably mounted on the forward end of said mandrel-bar, said mandrel-bar 30 having a valve chamber in its forward end, a valve in said valve chamber, said valve being normally spring-biased into closed position, an extension on the rear of said mandrel-plug which is operable to open said valve by the feeding 35 movement of a work-piece into the mill, a tube extending through said mandrel-bar and opening into said valve chamber, said mandrel-plug

having a bore in communication with said valve chamber when said valve is in open position, the tip of said mandrel-plug having at least one passageway extending from said bore to its periphery, and means for delivering a lubricant to 5 said tube.

2. In a pipe or tube mill, a mandrel-bar, a tapered mandrel-plug reciprocably mounted on the forward end of said mandrel-bar, said mandrel-bar having a valve chamber in its forward 10 end, a valve in said valve chamber, said valve being normally spring-biased into closed position, an extension on the rear of said tapered mandrel-plug which is operable to open said valve by the feeding movement of a billet into 15 the mill, a tube extending through said mandrel-bar and opening into said valve chamber, said tapered mandrel-plug having a bore in communication with said valve chamber when said valve is in open position, the tip of said tapered 20 mandrel-plug having at least one passageway extending from said bore to its periphery, and means for delivering a lubricant to said tube.

3. In a pipe or tube mill, a mandrel-bar, a mandrel-plug reciprocably mounted on the forward end of said mandrel-bar, said mandrel-bar having a passageway, means for delivering a lubricant to the passageway of said mandrel-bar, said mandrel-plug having a passageway which communicates with the passageway of said mandrel bar and extends to the periphery of said mandrel-plug, and means for controlling the flow of lubricant through the passageway of said mandrel-plug, said means being operable by the reciprocation of said mandrel-plug on the forward end of said mandrel-bar.

EDWARD J. NOVACK.
